Patented Aug. 20, 1912.

UNITED STATES PATENT OFFICE.

CHARLES HENRY FREEMAN, OF BLOOMINGTON, ILLINOIS

EXPLOSIVE-ENGINE STARTER.

1,036,213.

Specification of Letters Patent. Patented Aug. 20, 1912.

Application filed January 27, 1911, Serial No. 605,080. Renewed July 3, 1912. Serial No. 707,610.

To all whom it may concern:

Be it known that I, CHARLES H. FREEMAN, citizen of the United States, residing at Bloomington, in the county of McLean and State of Illinois, have invented certain new and useful Improvements in Explosive-Engine Starters, of which the following is a specification.

This invention relates to explosive engine starters, and belongs to that class of devices constructed and arranged to give to the shaft of an explosive engine a sufficient impulse to start the engine, and to permit the engine shaft to continue its revolution independently of the starter when once started.

Associated with such starting devices are usually found parts having the function of guarding the device from the effect of "backfire" of the engine, and this invention is provided with parts for that purpose.

The object of this invention is the production of an explosive engine starter wherein the various parts have special construction and particular relation to each other in form and arrangement, whereby it is believed that great convenience and effectiveness are attained.

This invention is illustrated in the accompanying drawings, of which—

Figure 1 represents the front of an automobile having this invention applied thereto. Fig. 2 is a longitudinal section of this invention on an enlarged scale of drawing. Fig. 3 is a cross-section of the starter cylinder on the line $x-x$ of Fig. 1. Fig. 4 is a section lengthwise, on an enlarged scale, of the igniter shown in Fig. 1. Fig. 5 is a fragmentary view, looking directly toward the free end of the pawl, showing its engagement with the end of the hollow shaft provided with the flange.

The same letter is employed to refer to the same part throughout the specification and drawings.

The front axle frame A of a motor vehicle, has suitably secured to it a curved cylinder comprising twin portions B and b, usually bolted together. The connected portions of the cylinder are best shown in Fig.

3. The solid shaft C of this invention is arranged at the center. That is to say, an imaginary median curved line within the cylinder would be described by taking the axis of shaft C as a center. The piston D within the cylinder follows such a curved line. The piston D is placed at the end of

an elbow crank c, that comprises a relatively straight portion carried by the shaft C, and a curved portion constructed to pass within the cylinder, and bearing the piston D. The 60 elbow crank c is loose on shaft C. One end of the curved cylinder is controlled by an air valve E, and a tube e for serving gasoline opens in the seat of the air valve, as illustrated in Fig. 1. An igniter F opening into the curved cylinder, is connected by suitable insulated conductors with a battery f, and with the cylinder through the battery. A collar G on the outer end of shaft C retains the parts thereon. Immediately 70 next the collar G, is a pulley g, and secured to the pulley is an operating cable H, that may be led to any distant point upon the vehicle.

The hub, or the circular portion of the 75 elbow crank c that rides shaft C is designated by the letter J, and it carries a bearing j for a rock-shaft K, that extends over the grooved pulley g, and is provided at the end with a small arm k, which projects 80 along the side of pulley g toward the center of the pulley, and in the path of lug L formed on the side of the pulley, as shown in Figs. 1 and 2. At the other end of the rock-shaft K is secured the pawl M, constructed to engage the teeth of the ratchet wheel m. The ratchet wheel is compelled to turn with the shaft C by reason of the engagement of the spline N of the ratchet wheel and the lengthwise groove n in the 90 shaft. Next to the ratchet wheel, on the left in Fig. 2, is the flange P of the hollow shaft Q and it will be noted that the flange P on the side toward the ratchet wheel is cut away annularly, with the result that 95 the flange and ratchet wheel together form an annular groove q, to be again mentioned. The flange P has a T-shaped groove formed in its face next the ratchet wheel, and marked R in Fig. 2. The groove is engaged by correspondingly shaped headed pins r, that pass into the side of the ratchet wheel. Thus, it is thought to be made out that while the flange may rotate with respect to the ratchet wheel m, a sidewise 100 movement of the flange will draw the ratchet wheel in the same direction. That is to say, if by the effect of some force, the flange P should be moved to the left from its position as illustrated in Fig. 2, the engagement of the headed pins and annular T-shaped slot would cause the ratchet wheel

to be moved in the same direction and to the same extent.

Within the hollow shaft Q, the solid shaft C is provided with an exteriorly threaded sleeve S, secured to the shaft C, and the threads have considerable inclination with respect to the axis of shaft C, as shown in Fig. 2. The hollow shaft Q is carried in bearing T forming a part of or supported by the axle frame A of the vehicle. The interior of the hollow shaft Q is provided with threads engaging and corresponding with the threads of the sleeve S. The threads within the hollow shaft are marked 8. That portion of the shaft C extending within the hollow shaft Q toward the left in Fig. 2 is of less diameter than the remainder, and it is encircled within the hollow shaft by the spring t, that bears in one direction against the sleeve S, and in the other direction against the hollow shaft.

In Fig. 2 are shown the ratchet teeth U at the end of the hollow shaft, adjacent to the ratchet teeth V, upon the end of the engine shaft v. Further considering Fig. 2, it will be noted that between the hub J of the elbow crank c, and the ratchet wheel m, there is a spiral spring W, and, as indicated in Fig. 1, the outer end of spring W is attached to the elbow crank c, and the other or inner end of spring W is secured to shaft C. The force of the spring must be overcome to move the piston from the position illustrated in Fig. 1, and, consequently, the spring W will return the piston D toward the position shown.

The remaining parts of this invention are advantageously described in connection with the explanation of its mode of operation.

Again considering Fig. 2, it will be understood that a flat spring w is secured upon the periphery of the hub or circular center J of the elbow crank. The spring w is relatively a strong spring, and its effect is exerted upwardly against the nose l that is secured to the rock-shaft K. That pressure acts to normally hold the movable end of pawl M toward ratchet wheel m and the flange P. But, let it be assumed that the cable H is drawn upon, thus turning pulley g and bringing lug L in contact with small arm k of rock-shaft K. As the rock-shaft rotates, the nose l presses the flat spring w down upon the hub J until it can go no farther, and the rock-shaft is held from turning. The movement of the rock-shaft described is, however, sufficient to raise the movable end of pawl M high enough to free the annular lip O of the pawl from its previous engagement with the inclined edge portion of the flange P, marked p. The hollow shaft is now no longer held in its position illustrated in Fig. 2, and the coil spring t encircling the reduced portion 7

of shaft c, within the hollow shaft acts to move the shaft lengthwise, and with it the ratchet wheel m by reason of the engagement of the T-groove and headed pins already described. The lengthwise movement of the hollow shaft Q brings into engagement the ratchet teeth U at the end of the shaft, and the corresponding teeth V at the end of the engine shaft v. It is desirable that the operator, before proceeding further, shall know that the teeth U and V are properly engaged, for the reason that injury might follow an explosion in the curved cylinder if those teeth were not fully engaged. It has been found that the operator can always determine whether or not the teeth U and V are completely in mesh, by the "feel" of the cable. That is to say, by alternately drawing upon the cable for a short distance, two or three times, the movement is communicated from the cable to pulley g, and by lug L and arm k to rock-shaft K and, consequently, to the elbow crank c. The spiral spring W, being attached to the elbow crank and to solid shaft C, the movement stated rocks the shaft C and threaded sleeve S yieldingly, and "settles" or adjusts the teeth U and V to each other, and, when they become finally engaged the operator readily detects the condition by the pull or "feel" of the cable H. Upon thus assuring himself that the ratchet teeth are fully engaged, the operator draws upon the cable and moves piston D in the curved cylinder a predetermined distance, usually, about one-half the length of the curved cylinder, and takes in a charge of explosive mixture through air valve E, and the gasoline inlet e that becomes uncovered as the air valve rises, 100 whereupon the cable is suddenly released. The release of the cable allows the flat spring w on hub J to throw nose l upwardly, turning rock-shaft K and moving the free end of pawl M into engagement 110 with the teeth of ratchet wheel m. The spiral spring W throws the piston D back into the cylinder, compressing the charge mechanically to a sufficient degree to force the piston disk 2 of igniter F outwardly 115 against its adjusting spring 3, thus separating the contacts 4 and 5, of which there are usually several, and exploding the charge in the curved cylinder. By means of nut 6 and spring 3, the piston disk 2 is adjusted for that pressure found by trial to be exerted by the return or spiral spring W. In practice, the disk piston is adjusted to move at a slightly lower pressure than the maximum of which the spring W is capable, so as to make sure of the sparking. Ordinarily, the turning impulse given by the explosion in the curved cylinder to the engine shaft v is ample to start the engine in the proper way. Let it be assumed, 125 130

however, that the explosion fails to start the engine as desired. A considerable portion of the exploded charge will be exhausted by way of the opening *a* which extends as shown in Fig. 3 for about one-half the length of the curved cylinder, and in which the elbow arm moves. The remaining portion of the exploded charge will pass the piston *D* by way of duct *d*, shown in Fig. 1, and the piston *D* will be returned with very little delay into its original position, enabling a new charge to be taken in and the operation described repeated.

It has been stated that the coil spring *t* within the hollow shaft *Q* moves the hollow shaft to the left and engages the ratchet teeth *U* and *V*. It has also been explained that the threads *s* and those of the threaded sleeve *S*, are very much inclined to the axis of the shaft, and the coil spring *t* is constructed of sufficient strength to keep the hollow shaft to the left, and teeth *U* and *V* engaged, in spite of the tendency of the turning threaded sleeve *S* to act upon threads *s* and draw the hollow shaft toward the right. The effect of spring *t* permits the exertion of a turning force or impulse ordinarily enough to start the engine. But, let it be assumed that extraordinary conditions arise, for example, that there is a "back-fire" of the engine while the pawl *M* and ratchet wheel *m* are engaged. The sleeve *S* will now be relatively stationary and the hollow shaft will turn backward, rotating flange *P* with respect to ratchet wheel *m*, compressing coil spring *t* and moving ratchet wheel *m* toward the right until the pawl no longer engages its teeth, that is to say, until it reaches the position substantially as shown in Fig. 2. As the lip *O* of the pawl meets the annular inclined surface *p* of the flange, the action of spring *w* presses those parts together and completes the movement of the flange *P* and the ratchet wheel *m* toward the right, at the same time effectively latching the flange against accidental movement toward the left. When the pawl engages the ratchet wheel the lip *O* of the pawl occupies the groove *q* formed by the meeting of flange *P* and ratchet wheel *m* as explained.

The actual form of the parts herein illustrated may be modified without departing from the purview of this invention.

Having now described this invention, and explained the mode of its operation, what I claim is:—

1. In an engine starter, the combination with a crank-carrying shaft, of an engine shaft, detachable connecting devices constructed and arranged to connect the said shafts, a curved cylinder constructed and arranged concentrically with the crank-carrying shaft, an elbow crank having a curved portion arranged in the cylinder, means

actuated by the movement of said connecting devices and constructed to connect the said crank and crank-carrying shaft, a piston attached to the curved portion of said crank within the cylinder, piping connected with the cylinder whereby fluid may be admitted to operate the piston, and a spring having one end attached to said crank and arranged to hold the piston yieldingly within the cylinder.

3. In an engine starter, the combination with a crank-carrying shaft, of an engine shaft, detachable connecting devices constructed and arranged to connect the said shafts, a curved cylinder constructed and arranged concentrically with said crank-carrying shaft, an elbow crank having a curved portion arranged within the cylinder, a piston attached to the curved portion of the crank within the cylinder, piping connected with the cylinder whereby fluid may be admitted to operate the piston, and a spring having one end connected with said crank and arranged to hold the piston yieldingly within the cylinder.

4. In an engine starter, the combination with a crank-carrying shaft, of an engine shaft, detachable connecting devices constructed and arranged to connect the said shafts, a curved cylinder constructed and arranged concentrically with the crank-carrying shaft, piping connected with the cylinder for serving fluid fuel thereto, an air valve arranged to admit air into the cylinder, an igniting device connected with said

cylinder, an elbow crank having a curved portion arranged in the cylinder, a piston attached to the curved portion of the crank within the cylinder, means actuated by the movement of said detachable connecting devices and constructed to connect said crank and crank-carrying shaft, a spring having one end connected with the crank and arranged to hold the piston yieldingly within

the cylinder, and means constructed and arranged to draw the piston outwardly against the force of the said spring.

In testimony whereof I affix my signature in presence of two witnesses.

CHARLES HENRY FREEMAN.
